UNITED STATES PATENT OFFICE

131,483

DESIGN FOR A CASING FOR SOUND REPRODUCING APPARATUS

David C. Rockola, Chicago, Ill., assignor to Rock-Ola Manufacturing Corporation, Chicago, Ill., a corporation of Delaware

Application November 24, 1941, Serial No. 104,273

Term of patent 3½ years

To all whom it may concern:

Be it known that I, David C. Rockola, a citizen of the United States, residing at Chicago, in the county of Cook and State of Illinois, have invented a new, original, and ornamental Design for a Casing for Sound Reproducing Apparatus, of which the following is a specification, reference being had to the accompanying drawings, forming a part thereof.

Fig. 2 is a side elevational view of the casing, the opposite side being similar;

Fig. 3 is a rear elevational view of the casing; and

Fig. 4 is a top plan view thereof.

I claim:

The ornamental design for a casing for sound reproducing apparatus, substantially as shown and described.

DAVID C. ROCKOLA.
